UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

OILING DEVICE.

Application filed March 3, 1926. Serial No. 91,938.

This invention relates to oiling devices, but more particularly to an oiling device which may be connected to a pressure fluid supply line for the purpose of supplying oil to fluid actuated machines, such as rock drills, pneumatic hoists and the like. In short, the present invention is contemplated for attachment to any pressure fluid supply line in which there are pulsations due to the admission and cut-off of pressure fluid in the engine to which such pressure fluid is being supplied.

One object of the invention is to deliver lubricant in suitable quantities to fluid actuated engines through the medium of the pressure fluid utilized for actuating such engines.

Another object is to insure proper delivery of different grades of lubricant. In the present instance this is accomplished by making the oil delivering element of the device adjustable.

Further objects will be in part obvious and in part pointed out hereinafter.

The invention consists of the features of construction and combination of elements substantially as hereinafter described and more particularly pointed out in the appended claims and illustrated in the accompanying drawings, in which

Figure 1 is a longitudinal sectional elevation of an oiling device.

Figure 2 is a plan view in section taken through Figure 1 on the line 2—2 looking in the direction of the arrows.

Figures 3, 4, 5 and 6 are fragmentary plan views illustrating a few positions which the adjustable delivering members may assume in practice.

Figure 7 is a view similar to Figure 1 showing a modified form of oiling device.

Figure 8 is a longitudinal sectional elevation showing still another modification of the invention, and

Figure 9 is a sectional elevation taken through Figure 8 on the line 9—9 looking in the direction of the arrows.

Referring to the drawings, the invention comprises a casing A having a wall B which divides the casing into an oil reservoir C and a fluid passageway D. The fluid passageway in this instance is threaded at its ends as at E for the reception of the ends of suitable conduits F and G which may

lead from a source of pressure fluid supply for delivering pressure fluid to a fluid actuated engine or engines, such as rock drills, pneumatic tools and motor hoists.

Suitable means are provided for establishing communication between the passageway D and the oil reservoir C for the purpose of admitting pressure fluid into said reservoir, and also for delivering oil from the reservoir into the passageway D. To this end a pair of members H and J, preferably of generally cylindrical formation, are inserted into the wall B to extend with corresponding ends into the passageway D and at their other ends into the reservoir C, preferably to a point near a wall K which in this instance forms the bottom of said reservoir. The members H and J in this instance are identical in all respects and either of the members may be used as a conduit for admitting pressure fluid into the reservoir or for conveying oil from the reservoir into the passageway D, depending upon the manner in which the casing A is attached to the main pressure fluid supply line, in other words, upon the direction of flow of pressure fluid through the supply line.

In the present instance the members H and J are provided with longitudinal conduits L which extend from the lowermost ends of the members to a point near the top ends thereof. Communication between the conduits L and the passageway D is preferably afforded by transverse conduits O formed through heads P of the members H and J. By thus forming the heads P on the members H and J, shoulders Q are formed on the members which cooperate with shoulders R in the wall B to form fluid tight joints between said members and the wall.

To the end that the members H and J may at all times be held firmly against the shoulders R in the wall B, springs S are seated on the heads P and at their other ends bear against suitable plugs T screwed into the roof of the passageway D. The plugs T are preferably of such diameter that upon their removal from the casing free access may be had to the members H and J. The members H and J in this instance are adjustable, that is, they may be rotated about their longitudinal axes. For this purpose screw slots U are formed across

the ends of said members adjacent the head P for the reception of a screw-driver or other suitable instrument, whereby said members may be manipulated.

As is well known, many devices of this character function in an efficient manner only when the particular grade of oil is used for which they are intended. They may be able to handle light, medium or heavy grades of oil, but if designed for one particular grade of oil, will not properly supply other grades. The reason for this is that the element which generally controls the flow of oil from the reservoir into the supply passage is the port or the outlet opening leading from the reservoir into the pressure fluid passageway. If this outlet opening is of very small diameter, obviously, only a light grade of oil may be used. However, a small outlet opening precludes the use of heavier grades of oil, and, on the other hand, if a large outlet opening is provided only a heavy grade of oil may be used, otherwise the oil reservoir will quickly be emptied, with the result that the engines to which the oil is being supplied becomes flooded. To overcome this objectionable feature, and to render the device capable of handling all grades of oil, the members H and J are made adjustable. These members may be adjusted to the positions shown in Figures 1 and 2. In these positions the transverse conduit O of the member H parallels the line of flow of pressure fluid through the main passageway D and the outlet opening of said conduit is directed counter to the flow of the pressure fluid. By thus adjusting the member H a direct flow of pressure fluid through said member into the reservoir is obtained. In these figures, the member J is also so adjusted that the conduit O of the member J lies in the same general direction as the flow of pressure fluid through the passageway. However, the outlet opening of the conduit O of the member J is pointed in a direction opposite to that of the corresponding outlet opening of the member H, so that, due to the flow of pressure fluid through the passageway D, a suction will be created at the outlet opening of the conduit O in the member J and thus draw the oil into the pressure fluid stream. The positions of the members H and J in the Figures 1 and 2 indicate the "full on" position, that is, the positions in which the maximum flow of oil from the reservoir into the passageway may be obtained.

As is, of course, understood, the present device is largely dependent for its efficient functioning upon the pulsations which occur in the pressure fluid supply due to the admission and cut-off of pressure fluid in the engine to which such pressure fluid is being supplied. The pressure fluid admitted into the oil reservoir creates a pres-

sure on the surface of the oil. Upon the admission of pressure fluid into the rock drill or engine, a slight-drop of pressure will occur in the supply line. In consequence, the pressure fluid in the reservoir will expand and raise the oil in the member J, or in the member H if the position of the device is reversed in the supply line. The oil thus raised is then drawn into the passageway D by the suction created by the pressure fluid following through the passageway.

In Figure 3 the member J is illustrated as being substantially in the same position as that shown in Figures 1 and 2, that is, the position in which the greatest force or suction is created at the outlet opening of the conduit O. The member H, however, is rotated so that its transverse conduit O occupies a position inclined somewhat toward the direction of flow of the pressure fluid. In this way, a lesser amount of pressure fluid is admitted into the reservoir and the flow of oil through the member J will, in consequence, be reduced.

Another method of reducing the flow of oil from the reservoir as well as the flow of pressure fluid into the reservoir is illustrated in Figure 4. In this showing the member H is rotated so that its conduit O extends transversely to the flow of pressure fluid through the passageway D and the member J is moved approximately an eighth of a turn. In these positions of the members H and J a minimum amount of pressure fluid will be admitted into the reservoir and due to the smaller area of the outlet opening of the conduit O in the member J exposed to the sucking action of the pressure fluid, a smaller quantity of oil will be delivered to the pressure fluid.

In Figure 5 both the members H and J are moved approximately one eighth of a turn from the "full on" position, thus showing still another means of reducing the flow of oil from the reservoir.

In the positions of the members H and J illustrated in Figure 6 it will be noted that both of the transverse conduits O occupy a position approximately at right angles to the direction of flow of the pressure fluid through the passageway D. In this position of the members H and J only a minimum quantity of oil will be supplied to the pressure fluid.

In the drawings, only a few of the positions which the members H and J may occupy for regulating the flow of oil from the reservoir are shown. It is, of course, to be understood that these members may be adjusted to any intermediate positions and that these showings are intended merely for illustrative purposes.

While, as hereinbefore stated, the present invention is primarily intended to accom-

modate different grades of oil it will be noted that by reason of the adjustable feature embodied in the device, a greater or lesser amount of oil of any grade may be delivered from the reservoir to supply immediate needs.

By means of this invention, I am enabled to use unusually large outlet openings in the conduits O, thus entirely eliminating clogging of the oil delivering conduits as so frequently occurs in similar devices in which only outlet openings of small diameter may be used.

In the modification shown in Figure 7, members V and W are inserted through the wall B of the casing A. The members V and W are in many respects similar to the members H and J in the preferred modification, but differ from the members H and J in that they are provided with relatively larger longitudinal conduits X in which may be inserted the ends of wicks Y. The wicks Y are preferably of such length that a considerable portion thereof may rest on the bottom of the reservoir C as illustrated, so that said wicks will be at all times immersed in the oil irrespective of any position which the device may occupy in practice. The members V and W are also adjustable to various positions in the wall B for regulating the delivery of oil into the pressure fluid stream. The members V and W like the members H and J in the preferred modification are also symmetrical, thus rendering the device reversible in the pressure fluid supply line.

In this modification, oil will be supplied by only one of the wicks Y, in the present showing, by the wick Y in the member W. The wick Y in the member V in this instance serves as an air filter to prevent the conveyance of any foreign matter which may be carried by the pressure fluid, thus also insuring a clean supply of lubricant at all times and eliminating the necessity of frequent cleansing of the reservoir C.

In the modification illustrated in Figures 8 and 9, a member Z substantially like the members H and J of the preferred modification is inserted in the wall B for the admission of pressure fluid into the reservoir C. In this instance, another member b, resembling somewhat the member Z, is also inserted in the wall B for delivering oil from the reservoir into the passageway D.

Suitable means are provided for atomizing the oil issuing from the outlet opening of the transverse conduit c. To this end an impeller d, mounted on a shaft e journaled in the member b, is arranged to rotate across the outlet opening of the conduit c. The impeller d may be of any suitable type and is rotated by the pressure fluid flowing through the passageway D, irrespective of any position which the member b, and con-

sequently the impeller d, may occupy with respect to the passageway D. The members Z and b in this instance are also capable of adjustment to positions suitable for supplying a required amount of oil to the pressure fluid flowing through the passageway D.

I claim:

1. An oiling device comprising a casing having a wall dividing said casing into an oil reservoir and a pressure fluid passageway, a pair of adjustable members extending through the wall into the passageway and into the reservoir, one of said members having a conduit therethrough for conveying pressure fluid from the passageway to the reservoir, a conduit through the other member for conveying oil from the reservoir to the passageway, and means for holding the members in placed position. 75

2. An oiling device comprising a casing having a wall dividing said casing into an oil reservoir and a pressure fluid passageway, a pair of adjustable members extending through the wall into the passageway and into the reservoir, one of said members having a conduit therethrough for conveying pressure fluid from the passageway to the reservoir, a conduit through the other member for conveying oil from the reservoir to the passageway, and springs transversely 90 through the passageway to bear against the members for holding said members in placed position. 95

3. An oiling device comprising a casing having a wall dividing said casing into an oil reservoir and a pressure fluid passageway, a pair of adjustable members extending transversely through the wall into the passageway and into the reservoir, a conduit through one of the members for admitting pressure fluid from the passageway into the reservoir, the inlet end of said conduit being normally directed counter to the line of flow of pressure fluid through the passageway, a conduit through the other member for conveying oil from the reservoir into the passageway, the outlet end of the conduit in the last said member being normally directed in the direction of the line of flow of pressure fluid through the passageway, and springs 110 pressing against corresponding ends of the members for holding said members in placed position. 115

4. An oiling device comprising a casing having a wall dividing said casing into an oil reservoir and a pressure fluid passageway, a pair of symmetrical members extending transversely through the wall into the passageway and into the oil reservoir, said members having longitudinal conduits communicating at corresponding ends with the reservoir and transverse conduits affording communication between the other ends of the longitudinal conduits and the passageway, said members being adjustable to regulate 120 125 130

the flow of pressure fluid through one of the members into the reservoir and to regulate the flow of oil through the other member from the reservoir into the passageway, wicks in the longitudinal conduits, the wick in one conduit serving to screen the air passing from the passageway into the reservoir

and the wick in the other conduit serving to deliver oil from the reservoir to the passageway, and springs acting against the members to hold them in placed position.

In testimony whereof I have signed this specification.

CHARLES C. HANSEN.
